UNITED STATES PATENT OFFICE.

ALLAN J. COLEMAN, OF CHICAGO, ILLINOIS.

HANDGRIP FOR PIPE AND SEWER RODS.

Application filed March 17, 1924. Serial No. 699,960.

This invention relates to improvements in automatic hand grips for sewer and drain pipe rods, the rods being provided at their advance ends with suitable tools, bits, or 5 the like for dislodging foreign matter from the walls of such sewer, drain pipe or the like. My improved automatic hand grip is adaptable for use with both flat, round, or other cross-sectional shaped rods used for 10 this and like purposes.

The object of the invention is to provide a very simple hand grip which is capable of being moved freely along the rod for the purpose of changing the point of connection 15 of the hand grip to the rod, and which is so constructed that the ordinary act of grasping the hand grip will automatically lock the grip on the rod and thereby securely 20 and temporarily fasten it to a new point on the rod. Further objects of the invention 25 are to produce a strong and rugged hand grip for the purpose set forth, a hand grip having interior clamping surfaces between which the rod extends, and which clamping 30 surfaces are brought to bear upon the rod in the ordinary manual use of the grip for operating the rod and to provide in a hand grip having such clamping surfaces a suitable fulcrum between relatively movable

parts of the hand grip.

A further object of the invention is to provide a hand grip of this character which can be economically made of malleable iron and like construction by a casting operation 35 and which requires little or no machine operations to finish the same, and the invention consists in the elements and combination of elements shown in the drawings and described in the specification and is pointed out 40 in the appended claims.

In said drawings showing two forms of the hand grip:

Fig. 1 is a side elevation of a hand grip, a rod to which it is attached, and a cleaning tool at the end of the rod remote from 45 the grip.

Fig. 2 is an enlarged elevation of the hand grip showing a portion of the rod.

Figs. 3 and 4 are cross and longitudinal 50 sections, respectively, on the lines 3-3 and 4-4 of Fig. 2.

Fig. 5 is a detached inner face view of one of the grip members.

Fig. 6 is a side elevation of another form 55 of hand grip.

Fig. 7 is a cross section on the line 7-7 of Fig. 6.

Fig. 8 is a view similar to Fig. 5 showing the inner side of one of the members of the hand grip illustrated in Figs. 6 and 7.

First referring to Figs. 1 to 5 inclusive, 60 10 designates, as a whole, my improved hand grip, 11 a flat elongated rod, and 12 a tool or spear point which is fixed to the end of the rod remote from the hand grip and is the part of the apparatus which attacks the dirt or sediment in the pipes to be cleaned. The rod shown in Figure 1 is a flat rod. It 65 will usually be made of spring metal of a gauge which can be spirally rolled for shipping.

Said hand grip comprises two separately formed members 14, 15. They are preferably of symmetrical form and dimensions throughout the main portions thereof, being 70 75 dissimilar in respect of the means by which they are pivoted together to operate as the jaws of a clamp. A hand grip for a flat rod is of oblong cross-section, as will appear from Figures 2 and 3. The said members 80 are parted in the general plane of the flat rod, when adapted to a flat rod, and are exteriorly formed at their outer ends to provide a bead 16 and are likewise formed at 85 their inner ends to provide pairs of beads 16'. The manner of pivoting or hingedly connecting the grip members at the inner end of the hand grip comprises deformable lugs 17 integral with a neck like portion 18 at the inner end of the grip member 15 which 90 lies between the beads 16'; and said lugs are adapted to be formed upwardly and inwardly about the sides of and on a seat 19 on the grip member 14 between said beads 16'. This pivot or hinge relation is a loose 95 one so as to adapt the members of the hand grip to rods of different dimensions.

20, 20 designate transverse clamping ribs formed on the inner sides of the opposing grip members 14, 15. They are located outwardly beyond the pivotal connection between the grip members formed by the lugs 17, as before described. Said clamping ribs 20 are formed on their proximate faces to engage the rod to which the hand grip is applied. When the rod is flat said ribs are flattened throughout their transverse length to form flat clamping faces to engage a flat rod. The engaging or clamping faces of these ribs extend inwardly beyond the inner 100 105 110

faces of the reduced neck, or said portions 18, 19, respectively, as best shown in Figs. 3, 4 and 5. The margins of the grip members at the side of the hand grip are straight and oppose each other. When the hand grip is not applied over a rod these straight margins abut against each other, but the engaging faces of the ribs 20 are sufficiently depressed below said straight edges that they do not at this time abut. When the hand grip is placed over a rod, which can be readily accomplished after the members are pivoted together by merely inserting the outer end of the rod through the flattened opening 21 between the neck 18 and seat 19 and between the ribs 20, (and which operation causes the outer ends of the grip members to separate in the manner indicated by the dotted lines in Fig. 4) the grip is in place and the manual act of clamping the grip in the hand will cause the members 14, 15 to be forced together and, through the coaction of their pivot connections and the ribs 20, will cause the bearing faces of said ribs to firmly grip the rod so that the rod can be moved endwise in either direction against considerable resistance for the purpose of manipulating the rod and its end tool to clear a drain or sewer pipe. The particular 30 implement or tool herein shown is of that form described and claimed in my copending application for U. S. Letters Patent Serial No. 699,961, filed on the 17th day of March, 1924, but so far as the present invention is concerned the prodding or dislodging tool may be varied.

In Figures 6, 7 and 8 is shown the type of hand grip adapted to a round rod of known form, usually made by spirally winding a 40 cylindric wire to constitute a flexible rod. These rods are somewhat more flexible than the rods illustrated in Figure 1 to follow the bends of drain pipes. The characteristics of the hand grip shown in Figures 6, 7 and 8 are, however, the same in principle as those shown in Figures 1 to 5 inclusive, with the exception that the grip members 22, 23 are made generally semi-cylindric and the clamping ribs 24 are semi-circular on their 50 clamping faces to engage the circular rod designated by 25. The other similar parts can be and are designated by like reference numerals applied to the parts shown in Figures 1 to 5 inclusive. In practice, the rod 55 25, which is so flexible that it can be made to follow devious courses in relatively small pipes, is provided with an advance dislodging implement or tool which is itself flexible so as to be capable of passing around 60 sharp bends in the pipe. A form of tool for this purpose can be made of a tapered spirally wound structure having, if desired, an external spiral and tapered thread or bit. The operation of the type of hand grip 65 shown in Figures 6, 7 and 8, in connection

with the round rod 25, is the same as that hereinbefore described and need not be repeated.

In the above forms of hand grip the pivot lugs 17, when the parts are cast, are disposed in planes substantially normal to the planes of the side edges of the members, and said members are assembled by fitting the narrow seat 19 between the initially straight lugs 17 and thereafter, by the use of a suitable tool, bending the ends of said lugs inwardly towards each other on the seat 19. This completes the assembly of the two members. It will thus be seen that the two member of the hand grip can be very economically constructed and can be assembled by unskilled labor. Further, little or no machine operations are required to adapt the grip to fit over the rods, the only machine operation which may be necessary being that of finishing the clamping faces of the ribs 20, 24.

It will be understood that the constructions shown are illustrative of two practical embodiments of the invention and that the details of such embodiments may be somewhat varied within the spirit and scope of the claims hereto appended.

I claim as my invention:

1. A hand grip comprising two generally symmetrical members, formed on their inner faces to provide an axial passage for a rod, one of said members being provided with external deformable pivot lugs, and the other member being provided with an external seat over which said lugs are engaged, in order to form between said members a hinge connection permitting them to swing relatively to each other about a transverse axis, said members being provided with internal opposing clamping faces to coact with a rod disposed axially within the hand grip.

2. In a hand grip two gripping members having internal gripping surfaces, one of said members having deformable pivot lugs and the corresponding part of the other member being adapted to interlock with said lugs when said lugs are bent towards each other and form a hinge connection between said members adapted to permit said members to swing relatively to each other about a transverse axis.

3. In a hand grip, two gripping members having internal gripping surfaces inwardly a short distance from one end, and one of said members having lugs projecting therefrom and loosely overlying the other member at said end to form a hinge connection between said members to permit them to swing relatively to each other.

In witness whereof I claim the foregoing as my invention, I hereunto append my signature this 28th day of February, 1924.

ALLAN J. COLEMAN.
